UNITED STATES PATENT OFFICE.

FRANK G. CALDWELL, OF WHEELING, WEST VIRGINIA.

DESIGN FOR A CLAMP FOR SHEET-METAL ROOFING-PLATES.

SPECIFICATION forming part of Design No. 30,630, dated April 25, 1899.

Application filed March 20, 1899. Serial No. 709,862. Term of patent 7 years.

To all whom it may concern:

Be it known that I, FRANK G. CALDWELL, a citizen of the United States, residing at Wheeling, in the county of Ohio and State of West Virginia, have invented or produced a new and original Design for a Clamp for Sheet-Metal Roofing-Plates, of which the following is a specification.

The leading and material feature of my design is the clamp made the subject of the illustration in the drawing, wherein the figure represents a perspective view.

The said clamp is made in the form of a strip having a base 1, a flange 2, lying at substantially right angles thereto, a flange 3, extending from the opposite end of the base 1

and at an acute angle to said base, and a lip 4 upon the end of the flange 3, which leads outwardly therefrom and extends at an acute angle to said flange. 20

What I claim as my invention is—

The design for a clamp for sheet-metal roofing-plates, substantially as shown and described.

In testimony whereof I have hereunto set my hand in presence of two subscribing witnesses.

FRANK G. CALDWELL.
